Primary Examiner — Marie D. Fast Horse*(74) Attorney, Agent, or Firm* — Peter J. Ims; Westman, Champkin & Koehler, P.A.(57) **CLAIM**

The ornamental design for a network device controller, as shown and described.

DESCRIPTION

FIG. 1 is a front view of a network device controller showing the new design;

FIG. 2 is a rear view of the network device controller;

FIG. 3 is a left side view of the network device controller;

FIG. 4 is a right side view of network device controller;

FIG. 5 is a top view of the network device controller;

FIG. 6 is a bottom view of the network device controller;

FIG. 7 is a first perspective view of the network device controller; and,

FIG. 8 is a second perspective view of the network device controller.

The broken lines in the drawings depict portions of the network device controller that form no part of the claimed design.
